United States Patent Office

Des. 213,731
Patented Apr. 1, 1969

213,731

AIRSHIP

William A. Hsi, 508 Fawn Drive,
San Anselmo, Calif. 94960

Filed Aug. 29, 1967, Ser. No. 8,424

Term of patent 14 years

Int. Cl. D12—07

U.S. Cl. D71—1

FIG. 1

FIG. 2

FIG. 3

FIG. 1 is a side elevational view of my flying balloon design.

FIG. 2 is a front elevational view thereof.

FIG. 3 is a top elevational view thereof.

The dominant features of my design reside in the solid line portions.

I claim:

The ornamental design for an airship as shown and, described.
